INVENTOR
John B. Anton,
BY Edward A. Lawrence,
his ATTORNEY.

UNITED STATES PATENT OFFICE.

JOHN B. ANTON, OF MONONGAHELA BOROUGH, PENNSYLVANIA.

CARBID MINER'S LAMP.

1,187,481.

Specification of Letters Patent Patented June 20, 1916.

Application filed March 22, 1916. Serial No. 85,771.

To all whom it may concern:

Be it known that I, JOHN B. ANTON, a citizen of the United States, and residing in the borough of Monongahela, in the county 5 of Washington and State of Pennsylvania, have invented or discovered new and useful Improvements in Carbide Miners' Lamps, of which the following is a specification.

My invention consists in a new and improved carbide miner's lamp.

The object in view is the provision of a lamp which will be of simple, compact, durable and inexpensive structure, wherein the gas will be presented to the burner tip at 15 uniform pressure, in a cleansed and cooled condition, free from water and mechanical impurities, and wherein the reflector may be readily removed and then replaced, and the burner tube and tip cleansed.

10 In the accompanying drawings, Figure 1 is a side elevation of my improved lamp; Fig. 2 is a central vertical section of the same; Fig. 3 is a horizontal section along the line III—III in Fig. 1, and Fig. 4 is a 15 vertical section along the line IV—IV in Fig. 2.

The following is a detailed description of the drawings.

10 A is the water tank provided with a filling port 1 having a hinged closure 2. From the bottom of tank A depends a threaded neck 3 into which is screwed the corresponding threaded neck of the carbide tank B. A tube 4 controlled by valve rod 5 admits water 5 from tank A to tank B.

C is an annular metal cup, having its inner end closed, set into the interior of the tank A and having its open end fixed in the front wall of said tank. The inner, closed end of 10 the cup C is connected by the elbow tube 6 with the carbide tank, the lower end of said tube extending through the bottom of tank A at one side of the tube 4, and the upper end of tube 6 extending through the closed 5 end of cup C, preferably at one side of the center thereof.

7 is a filter of felt, or some other absorbent material, in annular form, slipped up on the tube 4 against the bottom of the tank A, and held in place by the spring washer 8. The gas arising from the generating chamber into the tube 6 is thus filtered of the major portion of its impurities.

The open end of cup C is provided with a flaring annular flange 9 connected with the

annular wall of the cup by means of annular shoulder 10 which bears against the wall of tank A and enables the cup to be rigidly soldered or otherwise fixed in place. The annular wall of cup C is provided with a 60 screw thread 11, which may be conveniently pressed in the sheet metal of the cup.

D is the reflector provided with a polished concaved reflecting face 12 surrounded by a flaring annular flange 13.

65

14 is an annular neck concentric with the reflecting face 12 and extending rearwardly. Said neck has a thread impressed therein, so as to screw into the cup C. Surrounding the base of the neck 14 and merging into the 70 flange 13 is a narrow shoulder 15, and 16 is an annular gasket of rubber or other suitable material, so that when the reflector is screwed up into the cup, as shown, a gas tight joint is made between the cup and the 75 reflector.

A burner tube 17 extends axially through the reflector face 12, and 18 is a burner tip mounted in the outer end of the burner tube.

10 The gas ascending from the carbide tank B 80 is partially cleansed by the filter 7 and enters the interior of the cup C through the tube 6. The generation of gas is at a varying rate, so that the gas does not pass through the tube 6 at a constant pressure, 85 and, if the burner tip were fed directly from the tube 6, the illuminating flame would flicker and vary in intensity. However, the interior of the cup C provides a chamber of relatively great capacity wherein the gas has 90 an opportunity to expand and, as a result, the pressure in said chamber is substantially uniform, giving a flame of constant illuminating value.

95 The offsetting or lack of centering between the discharge end of the tube 6 and the inner end of the burner tube, prevents the direct feeding of the gas from the carbide tank to the burner tip.

100 It is thus evident that the gas is baffled or held back in the interior of the cup C and the gas pressure at the tip made uniform. The baffling of the gas in the interior of the cup C causes the mechanical impurities carried by the gas, such as small particles of 105 slaked carbide, to be precipitated, and thus prevents clogging of the burner tube and tip. Again, the inward protrusion of the cup C within the water filled tank A water-cools the walls of said cup and thus facil- 110

tates the precipitation of the moisture carried by the gas, and, by drying and cooling the gas, increases its illuminating value.

The socketing of the reflector in the cup contained in the water tank enables the reflector to be located close up against the front wall of the tank out of the way and less likely to be bumped against hard objects and bent out of shape when the lamp is worn on the miner's hat or under other conditions.

When the reflector becomes so damaged as to impair its usefulness, it may be unscrewed and a new one, obtained at slight expense, substituted.

When the burner tube or tip becomes clogged, the reflector may be unscrewed, the tip pushed out of the tube and the parts cleansed.

The construction is very simple, inexpensive and easy to manufacture, and forms a compact, strong, durable and attractive structure.

What I desire to claim is:—

1. In combination with the water tank and the carbid tank of a carbid lamp, an internally threaded cup socket having its open end fixed in the front wall of the water tank and bodily extending into the interior of said tank, a gas tube connecting said carbid tank with the inner end of said cup socket, a reflector, a burner fixed in the axis of said reflector, and an externally threaded annular neck concentric with and extending

rearwardly from said reflector and screwed into said cup socket, substantially as described.

2. In combination with the water tank and the carbid tank of a carbid lamp, an internally threaded cup socket having its open end fixed in the front wall of the water tank and bodily extending into the interior of said tank, a gas tube connecting the carbid tank with a point in the inner end of the cup socket at one side of the center of the latter, a reflector, a burner fixed in the axis of said reflector, and an externally threaded annular neck concentric with and extending rearwardly from said reflector and screwed into said cup socket, substantially as described.

3. In combination with the water tank and the carbid tank of a carbid lamp, an internally threaded cup socket having its open end fixed in the front wall of the water tank, and bodily extending into the interior of said tank, a gas tube connecting the carbid tank with a point in the interior end of the cup socket at one side of the center of the latter, a reflector, a burner of less capacity than said tube fixed in the axis of said reflector, and an externally threaded annular neck concentric with and extending rearwardly from said reflector and screwed into said cup socket, substantially as described.

Signed at Monongahela, Penna., this 20th day of March, 1916.

JOHN B. ANTON.
